UNITED STATES PATENT OFFICE.

ALBERT ARTHUR, OF CLEVELAND, OHIO.

DIE-SINKING MACHINE.

1,258,975.

Specification of Letters Patent. Patented Mar. 12, 1918.

Application filed August 20, 1915, Serial No. 46,500. Renewed June 11, 1917. Serial No. 174,164.

To all whom it may concern:

Be it known that I, ALBERT ARTHUR, a citizen of the United States, and a resident of Cleveland, in the county of Cuyahoga and State of Ohio, have invented a new and useful Improvement in Die-Sinking Machines, of which the following is a specification.

My invention is an improvement in die sinking machines, and the invention has for its object to provide a machine of the character specified of the turret type, wherein a new and improved arrangement of holding chuck for the work is provided, a new and improved type of suitable support and operating mechanism therefor, and a new and improved arrangement for supporting and mounting a cutter.

In the drawings:

Figure 1 is a side view of the improved machine,

Figs. 2, 4 and 5 are sections on the lines 2-2, 4-4 and 5-5, respectively, of Fig. 1, each looking in the direction of the arrows adjacent to the lines,

Fig. 3 is a front view of one of the cutters,

Fig. 6 is a section on the line 6-6 of Fig. 1,

Fig. 7 is a sectional view of the cutter,

Fig. 8 is a diagrammatic view of the belting,

Fig. 9 is a section through the bed or support at right angles to the section upon which Fig. 5 is taken,

Fig. 10 is a section of the bed parallel with the section shown in Fig. 1, but to one side thereof,

Fig. 11 is a top plan view of Fig. 12,

Fig. 12 is a side view of Fig. 11,

Fig. 13 is a front view showing the mechanism for moving the spindle vertically, and

Fig. 14 is a top plan view of the split nut, Figs. 9 to 14 inclusive, being on an enlarged scale.

The present embodiment of the invention comprises a supporting frame composed of a suitable base 1, upon which is mounted a sectional column composed of two sections 2 and 2^a, the sections of the column being connected together by bolts and nuts 3, and a head or top plate 4 is secured to the top of the upper section 2^a, by machine bolts or set screws 5.

The driving shaft 6 has keyed thereto a clutch sleeve 7, by means of a key or feather

8, and the sleeve is operated by means of a lever 9, which is pivoted at 10 to the base, and has a ring intermediate its ends which encircles the sleeve and is rotatably connected therewith as indicated at 11. This sleeve is enlarged internally as indicated at 12, and a solid shaft 13 is journaled in a block 14, extending upward from the base within the column, and the outer end of the shaft 13 has a head 15, which fits within the recess or enlargement 12 of the sleeve, and the inner end of the enlargement and the adjacent surface of the head have co-operating clutch teeth. When the sleeve is moved outwardly toward the driving shaft 6, the clutch teeth will be connected and the shafts 6 and 13 will rotate together.

The shaft 6 has a sleeve or hollow shaft 16 arranged thereon between the block 14 and the column wall, and the outer end of the sleeve extends through the wall and has an annular rib 17 at its outer end. A bevel gear 18 is keyed to the shaft between the sleeve or bushing 16, and a similar bushing 19 within the block, and this gear meshes with a bevel gear 20 on a vertical shaft 21, journaled at the axis of the column. The gear 18 is keyed to the shaft 13, and a larger gear 22 is keyed to the sleeve 16. This gear 22 meshes with a gear 23 on a hollow shaft 24, which encircles the shaft 21. The rib 17 and the adjacent end of the sleeve 7 have co-operating clutch teeth for a purpose to be presently described.

A pulley 25 is secured to the upper end of the hollow shaft above the column, and a belt 26 connects the pulley with a pulley 27 on a shaft 28, journaled parallel with the shafts 21 and 24, in a bearing bracket 29, connected with the top plate 4 of the column. The shaft 28 is provided at its lower end with a bevel gear 30, which meshes with a gear 31 on a shaft 32, journaled at right angles to the shaft 28 in a bearing bracket 33, mounted on a sliding arm 34, to slide on the column 2^a.

Referring to Fig. 4, it will be seen that this arm 34 has inwardly inclined flanges 35 and 35^a, which fit similarly shaped ribs on the column. This shaft 32 has a worm 37 at its outer end, and the worm meshes with a worm wheel 38 on a shaft 39, arranged at right angles to the shaft 32, and supported by the sliding arm in a manner to be described.

The cutter 40, to be presently described,

is connected to the shaft 39 by means of gear wheels 41 and 42, the former gear wheel being on the shaft 39, while the latter is an idler for connecting the gear 41 with the cutter 40. The cutter is supported by bearing arms 43 and 44, which are mounted to slide on a guide 45 at the front of the arm 34, and arranged transversely thereof. This guide has on its outer face an undercut rib, and the arms 43 and 44 have undercut grooves for engaging the ribs.

A threaded shaft 46 is journaled on the guide in an outstanding rib 47 at one end thereof, and the inner end of the shaft is rotatably connected with the arm 43. A hand wheel 48 is connected with the outer end of the shaft, and it will be evident that when the shaft is rotated the arm 43 will be moved toward and from the arm 44. This arm is so mounted in order to permit the removal and replacement of the cutters.

It will be noted from an inspection of Fig. 3 that the cutter 40 has a central opening 49, and each end of the opening is enlarged in tapering form as shown at 49^a. The arms 43—44 have half center extensions which engage the portions 49 to support the cutters, and these half center extensions are shaped to fit the enlargements 49^a, and each 30 half center extension fits one half of the enlargement. The arms are clamped on the guide 45 by means of bolts and nuts 50, two of the said bolts being provided for each arm. When using a wide faced cutter 35 it is necessary to move also the arm 44, hence this arm is also made movable, and is provided with the clamping bolts 50.

The cutter is fed by means of a hand wheel 51, which is secured to the outer end 40 of a shaft 52, journaled in the upper portion of the arm 34 and having a bevel gear 53, at its inner end, which meshes with a similar gear 54 at the upper end of a sleeve which is threaded onto a vertical shaft 55, 45 supported by the column. It will be evident that when the hand wheel 51 is rotated in the proper direction the arm may be raised or lowered with respect to the column.

When using a cutter of larger or smaller 50 diameter than that shown, the gear wheels 41 and 42 are moved backward or forward by means of a hand wheel 56, which is secured to the inner end of a threaded shaft 57, journaled in a substantially rectangular 55 open frame guide 58, extending inwardly from the center of the guide 45. The arm 34 before mentioned, consists of the vertical portion which engages the column, and parallel bars extending from the lower end 60 of the vertical portion to a connection with the outer end of the guide 45 (see Fig. 4), and the guide 58 is between these bars.

A block or carriage 59 is mounted to slide in the guide 58, the inner faces of the side bars of the guide being grooved to receive

ribs on the block, and the inner end of the shaft 57 has a threaded engagement with the carriage or block. The gear wheel 42 is journaled in this guide, which also supports the shaft 39. When a larger size cutter 40 70 is placed, it will be evident that the gear wheels 41 and 42 must be moved inwardly to provide for the proper meshing of the wheels and cutters.

It will be noted from an inspection of Fig. 4, that provision is made for permitting the detachment of the arm 34 from the column 2^a. The flange 35^a of the vertical portion of the arm is arranged to swing outward beyond the adjacent rib 36 of the column, and a wedge or gib 60 is arranged on the inner face of the flange.

The bracket 33 which supports the outer end of the shaft 32 is secured to the sliding block or carriage 59, and this bracket has 85 bearings on each side of the worm 37, the arrangement being such that the worm wheel or worm must move with the sliding carriage. Hence the relative position of the gears 41 and 42 is not changed, because they 90 move together, and the connection between the shaft 32 and the shaft 39 is not interrupted. The worm 37 is feathered to the shaft 32.

Preferably ball bearings are arranged between the pulley 25, and the pulley 61 arranged directly above the said pulley 25 and secured to the shaft 21. The upper end of the shaft 21 is supported by a bracket 62, and a ball bearing 63 is arranged between 100 the brackets, and washers 64, which are threaded on to the shaft. The bushing or sleeve 19 will be in practice of bronze pressed into the block 14, which is of cast iron, and into a bearing bracket 65, arising 105 from the base within the column 2.

Ball bearings are arranged between the respective bevel gears 18, 22, 20 and 23, and between the block 14 and the bearing bracket 65, and a similar bearing is arranged between the bevel gear 23 and a washer 66, which is threaded on to the hollow shaft 24, above the bevel gear.

A support or bed 67 is supported by the base in a manner to be described, and the 115 said bed or support supports a cross slide 68, a lateral slide 69, and a chuck 70. The support or bed 67 is mounted to move vertically on the base, by means of a column 71, which is internally threaded and provided with a screw.

A shaft 72 is journaled in a sleeve bearing 73, secured to the support or bed 67, and this shaft extends into the support or bed, and is provided with a pair of bevel or spiral gears 74, which mesh with the screw 75, for turning the said screw to cause the support to be raised or lowered with respect to the base.

It will be noted from an inspection of Fig. 130

5, that the bed or support 67 and the cross slide 68 extend into the column 2, the said column being open to permit this extension and the inner end of the cross slide 68 is recessed or notched at the shafts 21 and 24 to receive the said shafts during the movement of the cross slide. The support 67 has flanges 76 and 76^a, similar to the flanges 35 and 35^a of the arm 34, and these flanges 10 brace similarly shaped ribs 77 on the column.

A gib or key 78 is arranged at the flange 76^a, and this gib or key is pressed toward the rib by set screws 79. When the gib or key is released the flange 76^a may be disengaged from the adjacent rib. The chuck 70 is hinged to the lateral slide 69 at the outer side of the chuck as indicated at 80, and the chuck has depending arc-shaped slotted arms 81, which pass through openings in the lateral slide 69 and into a recess in the cross slide 68, and the outer or concave edges have rack teeth with which engage pinions 82, secured to a shaft 83, journaled parallel with the direction of motion of the lateral slide 25 69. This shaft also carries a spiral gear 84, which engages a spiral gear 85, secured to a shaft 86, extending at right angles to the shaft 83, and having its outer end polygonal for engagement by a tool.

30 It will be evident that when the shaft 86 is turned the chuck may be raised or lowered through the engagement of the pinions 82 with the teeth of the bars 81. The body 87 is mounted on the chuck, and this body is 35 circular, having an axial pin 88, which is journaled in the chuck, and the periphery of the body is provided with teeth which are engaged by a worm 89 on a shaft 90, which is journaled in the chuck, and is provided 40 with a hand wheel 91, at its outer end for convenience in turning the same.

It will be evident that when the shaft is rotated by the hand wheel the chuck body will be rotated on the chuck. This shaft is 45 at the hinge upon which the chuck turns. The body has a flange or rib 92 at its periphery, and clamping blocks 93 are provided for engaging above the rib to hold the chuck body in place. These clamping blocks 50 93 are secured to the chuck by bolts as shown, and while they do not interfere with the rotation of the body they prevent upward movement thereof, and provide means for clamping the chuck rigidly in any desired 55 position.

Gripping means is provided for gripping the work. The said means comprises two jaws 94, which have ratchet teeth on their under faces coöperating with similar teeth 60 on the chuck body, and each jaw has in addition a hook 95 at each end, which engages beneath the squared portion of the body to prevent upward movement of the jaws. The ratchet teeth of the jaws and the body are 65 shaped to prevent outward movement of the

jaws away from each other, and a series of set screws 96 is threaded through each jaw.

The chuck body above the circular portion has a squared or flat portion 87^a, and the gripping means is mounted on this flat 70 portion. A lead screw 97 is journaled on the cross slide 68, and this stationary lead screw has a pinion 98, which meshes with a spiral gear 99 on a shaft 100, journaled at an angle to the shaft 97 and having its outer 75 end polygonal for convenience in rotating the same.

This shaft or lead screw 97 is a feeding mechanism for the lateral slide 69, and it will be noted from an inspection of Fig. 9 80 that the nut 155 through which the lead screw is threaded carries the spiral gear 98, and on the nut on each side of the spiral gear, is arranged a collar 156. The lead screw 97 is mounted on the lateral slide, and 85 it will be evident that when the shaft 100 is rotated the nut 155 will be rotated and the lateral slide will be moved together with the lead screw transversely of the cross slide.

The cross slide 68 is fed by a shaft 101 90 suitably connected with the slide to move the same when the shaft is rotated. The pulley 61 is belted to a series of pulleys 102, 103, 103^a, 104, 105 and 106 by means of a belt in a manner to be later described, the said pulleys being mounted in a manner to be also 95 later described.

The column 2^a is provided with a radial extension or guide 107, and a carriage 108 is mounted to move laterally on the extension or guide. The extension or guide has laterally extending ribs 109 at its front, and these ribs engage in grooves 110 and 110^a in the carriage. The groove 110 is of larger diameter than the rib which engages it, and 105 a gib or key 111 is arranged in the groove and is connected to the carriage by a connection 112, to be later described.

A shaft or spindle 113 is journaled in a hexagonal slide 114, which is mounted to 110 move vertically in a guide 115, supported at the center of the carriage and secured thereto. The guide 115 has laterally extending ears 116, which lap upon the outer face of the carriage and are bolted thereto. The 115 spindle has a chuck or tool holding socket 117, and the chuck holds cutting tools, not shown. The tools may be made to describe a circle by means of a radius arm 118, and a slide block 119, which is connected to the 120 spindle slide 114, by means of a pin 120.

The pin 120 engages a threaded opening in the adjacent surface of the slide, and the block is moved in the radius arm, by means of a threaded rod 121, which is journaled 125 in the arm and has a threaded engagement with the block. When the radius arm is turned or rotated, the block will describe a circle or an arc of a circle which can be varied from naught to any desired radius 130

by changing the position of the block with respect to the scale 121—that is, by moving the block in or out with respect to the axis of rotation of the radius arm.

- 5 The radius arm is operated by means of a worm wheel 122, and a worm 123 of a worm shaft 124 mounted in the chambered guide 107. The worm shaft has a hand wheel 125 at its outer end for convenience in manipulating the same. The radius arm as shown in Fig. 1, may be rotated on its spindle 126 to which the worm wheel 122 is secured. This spindle is journaled in the guide 107, and the shaft 124 extends out of the guide 15 at the outer end thereof. The outer end of the threaded rod 121 is polygonal for engagement by a tool to rotate the same, and the rod is held from longitudinal movement in the radius arm by collars 127, each 20 of which is held in adjusted position by means of a set screw.

When the hand-wheel 125 is turned the radius arm is rotated and the axis of connection between the block carried by the radius 25 arm and the spindle bearing describes a circle or an arc of a circle and the point of the cutter which is held in a chuck 117 will describe the same circle or arc of a circle, the rotating block causing the spindle to be 30 raised and lowered relative to the carriage, and causing the carriage to be moved back and forth on its guideway so that the circular movement is imparted to the point of the cutter as above stated.

35 When it is desired to use the spindle 113 without the radius arm as an ordinary milling machine, the sliding block 119 is disengaged from the threaded rod 121 by means of a split nut, whose sections are indicated at 150 and 150^a, respectively. The sections of the split nut are moved in opposite directions by means of a rod 128, having a threaded portion intermediate its ends for engaging threaded openings in the sections of the nut.

This threaded portion of the rod consists of two portions which are threaded in opposite directions, and the openings of the nut sections are similarly threaded so that when 40 the rod is turned in one direction, the sections will be moved toward each other into engagement with the threaded rod 121, while when the bolt is turned in the opposite direction the sections will be moved 45 apart to release the nut from the rod. When the radius arm is disengaged, the spindle is moved vertically by means of a hand wheel 129, connected to a shaft 130, which is journaled in bearings 151, and the 50 shaft has a pinion 152, which meshes with the teeth of a rack 153, on the slide 114 of the spindle.

As shown in Fig. 8, the belt 131 is passed around the pulley 61, one run passing over 55 the pulleys 103 and 104, then over the arm

102 and back over the pulley 105, from thence over the pulleys 106 and 103^a to the arm 61. The pulleys 103—104—105 and 106 are in alinement, and in a line parallel with the line through the axis of the pulleys 102 70 and 61.

The arrangement is such that the pulleys 61 and 102 are almost completely encircled by the belt, thus insuring a firm grip of the same on the pulleys, and this grip is 75 maintained whatever the position of the pulleys 102, 104 and 105 with respect to the others. It will be understood that these three pulleys travel with the carriage. The mounting of these pulleys is shown in Fig. 80 6, wherein it will be noted that the pulley 105, which is an idler, together with the pulleys 103, 103^a, 104, 105 and 106 is supported by ball bearings above and below the pulley, the balls being arranged in races 85 and held in place by nuts 132 threaded on the pulley spindle.

The spindle consists of two portions 133 and 133^a of unequal diameter and the ends of the spindle are threaded. One of these 90 threaded ends engages a threaded opening in a bearing plate 135, which is secured to the carriage by bolts 134, and the other portion is engaged by the nuts. All of the pulleys just mentioned, as also the pulleys 61 95 and 102, have marginal flanges 136 at their lower ends for preventing the downward movement of the belt.

The operation of the improved machine is as follows:—The shaft 6 being driven, 100 when the clutch lever 9 is moved outwardly at its upper end the sleeve 7 will be connected to the shaft 13 and through the bevel gear connection 18—20 the shaft 21 will be driven, thus driving the shafts 28, 32 and 105 240. When the lever 9 is moved in the opposite direction, that is, its upper end inward, the clutch teeth of the sleeve 7 will engage with the teeth of the rib 17 and the hollow shaft 16 will be connected 110 to the hollow shaft 24 through the bevel gear connection 22—23. Thus either the pulley 25 or the pulley 61 may be connected with the driving shaft 6, but both cannot be connected at the same time.

When it is desired that the point of the cutting tool held in the chuck 117 of the spindle 113 describe a circle, the sliding block is connected to the radius arm, while when it is desired to use the mechanism on the guide 107 for machining, the block is disconnected from the radius arm by means of the split nut and the spindle is fed by the hand wheel 129.

The column 2^a will rotate about its axis to 125 bring either the cutter 40 or the spindle 113 above the work supporting table or chuck. This chuck may be tilted, rotated, adjusted transversely of the column, or toward or from the column, and the spindle may be 130

moved vertically or it may be moved toward or from the column. The cutter 40 may be moved vertically with respect to the column and cutters 40 of different size may be used.

5 It will be noted from an inspection of Figs. 3 and 7 that the cutter 40 has teeth on its periphery for engagement by the adjacent gear wheel 42 to drive the cutter while at the same time it has cutting edges 10 137. In addition it has peripheral cutting edges 138, the said edges being parallel with the axis of the cutter. The shaft 13 drives the spindle through the bevel gear connection 18—20, the shaft 21, the pulley 61 and 15 the belt 131. The hollow shaft drives the cutter 40 through the bevel gear connection 22 and 23, and the belt 26.

It will be understood that the ribs 60, 78, 111 and 158 are all held in place in the same 20 manner, that is, by means of a cap bolt, and set screws on each side of the bolt to permit the rib to be adjusted. This connection is indicated at 60^a in Fig. 4, at 79 in Fig. 5, at 112 in Fig. 6, and at 159 in Fig. 9. It will 25 be noted that each of the gibs 60, 78, 111 and 158 is provided with bearing faces at an angle to each other and at varying angles with respect to the back or outer face of the rib, and since each rib is held in place 30 by a cap bolt with a series of set screws at each edge of the rib, it will be evident that each rib or key may be adjusted to take up or compensate for wear on the rib or on the side of the element to which the rib is connected. As for instance, in Fig. 5, the rib or key may be moved away from the rib 76^a by turning the cap bolt or bolts in the proper direction.

When the set screws of each side are 40 turned into contact with the gib, the gib is held in absolutely true position. It will be understood that when the rib is of any length the set screws at each side of the cap bolt or bolts are several in number, extending 45 from one end of the gib to the other, and with a long gib several bolts would be used.

When the set screws are tightened at each edge of the gib, the gib is forced against 50 the face of the undercut rib and also against the side of the guide, thus taking up the wear on the front of the guide and upon the side. The bolts are then tightened to prevent the set screws from becoming loosened 55 by vibration.

The improved machine is especially designed for making dies for forging machines such as drop-hammer presses and up-setting machines, and also for making molds for 60 glass or rubber goods and the like, and mechanism is provided for permitting every operation upon these molds or die blocks to be done. Either the cutter 40 of the spindle 113 may be brought into position over the 65 table or bed 67 and this table or bed may be

adjusted to bring the articles into position to be operated on by the cutter or by a tool on the spindle.

In Fig. 1 the distance from the center of the pin 120 to the center of the trunnion 126 70 is about $\frac{5}{8}$ ". The distance from the outer side of the slide 108 to the end of the arm 107 is about $1\frac{1}{4}$ ". Therefore, when the block 119 is at the outer end of the radius arm and the radius arm is turned around by 75 means of the hand wheel 125, shaft 124, worm gear 122—123, the slide 108 will travel to the outer end of the arm 107. The sliding block in the radius arm is never disconnected when using the hand wheel 125. 80 However, when I wish to use the hand wheel 129 and the mechanism connected therewith, the radius arm is brought to a vertical position, as shown in Fig. 6, the block in the radius arm is disconnected, and the spindle 85 is raised and lowered by means of the hand wheel 129. This length of travel is limited to the length of the radius arm, but the said length is all that will be necessary, for the work support may be raised and lowered to 90 accommodate any work placed on the machine.

I claim:—

1. In a machine of the character specified, a support having a lateral arm, a carriage 95 having guided movement on the arm toward and from the support, a spindle having a chuck at its lower end, a radius arm journaled on the lateral arm and having a guide extending radially thereof, a block slideable 100 in the guide, means for moving the block and for holding it in adjusted position, said means being releasable from the block, a bearing for the spindle, a connection between the bearing and the block, means for 105 rotating the radius arm, a support below the lateral arm, said support being mounted for movement toward and from the first-named support and toward and from the lateral arm, a chuck mounted for movement transversely of the support, and means on the chuck for holding the work.

2. In a machine of the character specified, a support having a lateral arm, a carriage having guided movement on the arm toward 115 and from the support, a spindle having a chuck at its lower end, a radius arm journaled on the lateral arm and having a radial guide, a block slideable in the guide, means for moving the block and holding it in adjusted position, said means being releasable from the block, a bearing for the spindle, a connection between the bearing and the block, and means for rotating the radius arm. 120

3. In a machine of the character specified, a column having a lateral guide, a carriage movable on the guide toward and from the column, means for moving the carriage, a spindle journaled in the carriage, means for 130

driving the spindle, a slide in which the spindle is journaled, a radius arm pivoted to the guide, means for rotating the same, a block having guided movement in the arm, 5 and means for moving the block and holding it in adjusted position, the block being detachable from the said moving means.

4. In a machine of the character specified, a column having a lateral guide, a carriage 10 movable on the guide toward and from the column, means for moving the carriage, a spindle journaled in the carriage, means for driving the spindle, a slide in which the spindle is journaled, a radius arm pivoted to the guide, means for rotating the arm, a block having guided movement in the arm, 15 means on the radius arm for moving the block with respect thereto and for holding the block in adjusted position, said means being detachable from the block, and manually operated means for moving the spindle vertically when detached from the radius arm.

5. In a machine of the character specified, 25 a column having a lateral guide, a carriage movable on the guide toward and from the column, means for moving the carriage, a spindle journaled in the carriage, means for driving the spindle, a slide in which the 30 spindle is journaled, a radius arm pivoted to the guide, means for rotating the arm, a block having guided movement in the arm, and means on the radius arm for moving the block and holding it in adjusted position.

6. In a die sinking machine, a carriage having a vertical slide, a bearing movable in the slide, a spindle for the bearing, a support upon which the carriage is movable laterally, means for moving the carriage, 40 a radius arm pivoted to the support and having a guideway, a block movable in the guideway, a threaded rod journaled longitudinally of the guideway, a detachable connection between the block and the rod for moving the block when the rod is rotated, and a connection between the block and the bearing for the spindle.

7. In a die sinking machine, the combination with the spindle, the bearing for the spindle in which the spindle is journaled, a carriage for supporting the bearing, a radius arm pivoted to the support, and having a guideway, a block movable in the 55 guideway, means for moving the block, said means being detachable from the block, a connection between the block and the bearing, and means for moving the spindle vertically.

60 8. In a die sinking machine, the combination with the spindle, the bearing for the spindle in which the spindle is journaled, a carriage for supporting the bearing, a radius arm pivoted to the support, and having a guideway, a block movable in the 65

guideway, means for moving the block, said means being detachable from the block, and a connection between the block and the bearing.

9. In a die sinking machine, the combination with the spindle, of the support upon which the spindle is journaled and movable longitudinally, a radius arm pivoted to the support, a block movable radially on the arm, moving means for the block on the arm and having a releasable connection with the block, and a connection between the block and the spindle for constraining the spindle to move with the block while free to rotate with respect thereto. 70

10. In a die sinking machine, the combination with the column, consisting of upper and lower sections, the upper section being rotatable on the lower section, and means for clamping the sections together, a 85 bed for a chuck movable vertically with respect to the column, a slide mounted on the bed to move radially toward and from the column, said column having an opening at the lower section for permitting the inner end of the slide to enter the column, and a laterally moving slide mounted on the radial slide for lateral movement with respect thereto, said lateral slide carrying a work holding chuck, and tool holding supports connected with the upper section of the column. 90

11. In a die sinking machine, a column for supporting the tools, a bed adjacent to the column, a slide mounted to move on the bed toward and from the column, and of greater length than the bed, the column having an opening for permitting the inner end of the slide to enter the column, means for moving the slide on the bed, 100 and a work holding chuck supported by the slide. 105

12. In a die sinking machine, the combination with the column having a plurality of tool supporting means, of an operating shaft 110 for one of the said means, a hollow shaft journaled on the operating shaft for operating the other of the said means, a driving shaft, a connecting shaft in alinement therewith and having a driving connection with the first-named shaft, a hollow shaft on the connecting shaft and having a driving connection with the first-named hollow shaft, a sleeve feathered on the driving shaft and journaled on the connecting 115 shaft, means for moving the sleeve in opposite directions, and clutch mechanism in connection with the sleeve and the connecting shaft and in connection with the sleeve and the last-named hollow shaft and operated by 120 the movement of the sleeve in opposite directions.

13. In combination, a driving shaft, a driven shaft in alinement therewith, a sleeve feathered on the driving shaft and jour- 125

naled on the driven shaft, a hollow shaft on the driven shaft, means for moving the sleeve in opposite directions, and clutch mechanism in connection with the sleeve, 5 the driven shaft and the hollow shaft and controlled by the movement of the sleeve in opposite directions.

14. In a machine of the character described, a support constituting a guideway, 10 a carriage movable along the same, a spindle adapted to be provided with a working tool, said spindle being journaled in the carriage and adapted to be moved in an endwise direction relative thereto, means for rotating the spindle, and means, operable from a single point for simultaneously shifting the spindle in an endwise direction and for shifting the carriage so as to cause the working end of the spindle to describe an arc of 20 a circle.

15. In a machine such as described, a carriage, a support constituting a guideway along which said carriage may move, a spindle journaled in the carriage and adapted to be provided with a working tool, means for rotating the spindle, a rotary member carried by the support and operatively connected to the spindle, and means for turning said member so as to cause the 30 working end of the spindle to describe an arc of a circle.

16. In a machine of the character described, a carriage, a support constituting a guide way along which said carriage is 35 adapted to be moved, a spindle adapted to be provided with a working tool, said spindle being journaled in the carriage and movable in an endwise direction relative thereto, and means carried by the support 40 and adapted to be operatively connected to the spindle for simultaneously shifting the spindle relative to the carriage and for shifting the carriage along the guideway so as to cause the working end of the spindle 45 to describe an arc of a circle.

17. In a machine of the character described, a support constituting a guideway, a carriage movable along the same, a spindle adapted to be provided with a working tool, 50 said spindle being journaled in the carriage and adapted to be moved in an endwise direction relative thereto, a rotary member carried by the support, means whereby said member may be operatively connected to the spindle, means for rotating said member so as to cause the working end of the spindle to describe an arc of a circle, and means whereby the radius of 55 the described arc may be varied.

18. In a machine of the character described, a carriage, a support therefor constituting a guideway along which the carriage is adapted to be moved, a spindle adapted to be provided with a working tool, 60 said spindle being journaled in the carriage

and adapted to be given an endwise movement relative thereto, a rotary member carried by the support and adapted to be operatively connected with the spindle, means for operatively connecting and disconnecting said member and spindle, and means for rotating said member so as to cause the working end of the spindle to describe an arc of a circle. 70

19. In a machine of the character described, a carriage, a support therefor constituting a guideway along which the carriage is adapted to be moved, a spindle journaled in the carriage and adapted to be given an endwise movement relative thereto, 80 a rotary member carried by the support, means for operatively connecting and disconnecting said member and spindle, means for rotating said member so as to cause the working end of the spindle to describe an arc of a circle, and means for varying the radius of the described arc. 85

20. In a machine of the character described, a carriage, a support therefor constituting a guideway along which the carriage is adapted to be moved, a spindle and a bearing therefor carried by the carriage, means for rotating the spindle, said spindle having a working end adapted to be provided with a tool, a rotary member 90 carried by said support and having a connection with the bearing for the spindle, and means for turning said member whereby the working end of the spindle may be turned through an arc of a circle. 100

21. In a machine of the character described, a carriage, a support along which said carriage is adapted to be moved, a spindle journaled in said carriage, means for rotating the spindle, a rotary device carried by said support and having a member movable toward and from its axis of rotation and adapted to be operatively connected to the spindle, and means for turning 105 said device. 110

22. In a machine of the character described, a carriage, a support constituting a guideway along which said carriage is adapted to be moved, a spindle journaled in said carriage, means for rotating the spindle, a rotary arm carried by the support and having a member adjustable lengthwise thereof toward and from its axis of rotation, said member adapted to be operatively connected to and disconnected from the 120 spindle, and means for rotating said arm. 115

23. In a machine of the character described, a carriage, a support constituting a guideway along which said carriage is adapted to be moved, a spindle and a bearing therefor supported by said carriage and adapted to be provided with a working tool, a radius arm rotatably supported by said support and having a member carried thereby and movable toward and from its axis of 125 130

- rotation, means whereby said member may be connected to the spindle bearing, and means for rotating said arm.
24. In a machine of the character described, a carriage, a support constituting a guideway along which said carriage may be moved, a spindle journaled in said carriage, means for rotating the same, an arm rotatably supported by said support, a member operatively connected with the spindle and carried by said arm, means for adjusting said member toward and from its axis of rotation, and means for rotating the arm.
25. In a machine of the character described, a support constituting a guideway, a carriage movable along said guideway, a spindle journaled in said carriage and movable in an endwise direction, means for rotating the spindle, an arm rotatably supported by the support and having a member adapted to be operatively connected with the spindle, means for rotating the arm and means for connecting and disconnecting said member and the spindle.
26. In a machine of the character described, a carriage, a support constituting a guideway along which said carriage may be moved, a spindle journaled in said carriage, means for rotating the same, an arm rotatably supported by said support, a member adapted to be operatively connected with the spindle and carried by said arm, means for adjusting said member toward and from its axis of rotation, means for rotating the arm whereby the end of the spindle will describe the arc of a circle, and means for connecting and disconnecting the said member and the spindle.
27. In a machine of the character described, a carriage, a support constituting a guideway along which said carriage is adapted to be moved, a spindle rotatably supported by said carriage, and means for rotating the spindle, said spindle being movable in the direction of its length and at right angles to the direction of movement of the carriage, a rotary arm carried by the support and adapted to be operatively connected to the spindle, and means for turning said arm.
28. In a machine of the character described, a support constituting a guideway, a member movable along said support, a spindle and bearing carried by said member and movable in a direction at right angles to the movement of said member on the support, an arm rotatably supported by said support and adapted to be connected to said bearing, and means for rotating the arm.
29. In a machine of the character described, a support constituting a guideway, a member movable along said support, a spindle and bearing carried by said member and movable in a direction at right angles to the movement of said member on the support, an arm rotatably supported by said support and adapted to be connected to said bearing, means for rotating the arm to cause the end of the spindle to describe an arc of a circle and means for varying the radius of the arc which is thus described.
30. In a machine of the character described, a support constituting a guideway, a member movable along said support, a spindle and bearing carried by said member and movable in a direction at right angles to the movement of said member on the support, an arm rotatably supported by said support and adapted to be connected to said bearing, means for rotating the arm to cause the end of the spindle to describe an arc of a circle, means for varying the radius of the described arc, and means for disconnecting said device from the bearing.
31. In a machine of the character described, a support constituting a guideway, a member movable along said support, a spindle carried by said member and movable in a direction at right angles to the movement of said member on the support, an arm rotatably supported by said support and adapted to be operatively connected to and disconnected from the spindle, means for rotating the arm to cause the end of the spindle to describe an arc of a circle, and means for raising and lowering the spindle when disconnected from the arm.
32. In a machine of the character described, a horizontal support constituting a guideway, a carriage movable lengthwise of said support, a vertical spindle having a bearing carried by said carriage, means for rotating the spindle, an arm rotatably supported by said support and adapted to be connected with said bearing, and means of rotating said arm to cause the working end of the spindle to describe an arc of a circle.
33. In a machine of the character described, a horizontal support constituting a guideway, a carriage movable lengthwise of said support, a vertical spindle having a bearing carried by said carriage, means for rotating the spindle, an arm rotatably supported by said support, a member movable lengthwise of the arm, and having a detachable connection with said bearing, and means for raising and lowering the spindle when said member is detached from the spindle.

ALBERT ARTHUR.

DISCLAIMER

1,258,975.—*Albert Arthur*, Cleveland, Ohio. DIE-SINKING MACHINE. Patent dated March 12, 1918. Disclaimer filed November 17, 1933, by the patentee.

Hereby disclaims:

(a) From claim 15 any machine in which the "spindle" is not moved in a plane during the operation of the machine, and in which the "working end of the spindle" is not provided with means for supporting a working tool the end of which is moved in an arc of a circle.

(b) From claim 20 any machine in which the axis of the "spindle" is not maintained in a single plane during operation of the machine.

(c) From claim 21 any machine in which the axis of the "spindle" is not moved in a plane during the operation of the machine, and in which the "spindle" does not have a working end provided with means for attaching the working tool thereto, the end of which tool is moved in the arc of a circle during operation of the machine.
